UNITED STATES PATENT OFFICE.

FRED GUSTAF BROMAN, OF PHILADELPHIA, PENNSYLVANIA.

ANTISLIPPING MEANS.

Application filed November 17, 1924. Serial No. 750,350.

To all whom it may concern:

Be it known that I, FRED GUSTAF BROMAN, a citizen of the Republic of Finland, and a resident of the city of Philadelphia, State 5 of Pennsylvania, have invented a new and useful antislipping means to be used in connection with all kinds of coasting sleds to obtain a firm grip with the foot on ice or snow to push the vehicle in a forward direction 10 or to stop same quickly, also to be used on both feet for the purpose of obtaining a firm grip on ice or snow-covered roads, on slippery surfaces, or for mountain climbing.

Following is a full and exact specification, reference being had to the accompanying drawings, wherein:

Fig. 1 is a perspective view of a snow-gripper according to my invention; Fig. 2 is a calk, specially sharpened, of which two 20 or more are screwed in the bottom of the snow-gripper; Fig. 3 shows the snow-gripper fastened to a shoe.

The snow-gripper is made of malleable iron, cast steel or any other strong material 25 and is flanged at both sides in such a way that the sole of the shoe, to which it is attached is pressed between the flanges 1 (Fig. 1) and the broad ends 2 of the two or more calks, which are screwed in the bottom of 30 the snow-gripper (Fig. 1). These calks are forged of high grade steel or made of any other strong material and are sharpened in chisel form in such a way as to obtain the best grip on ice, snow or any other slippery 35 surface. The chisel-sharpened calks are furthermore formed in such a way that they can be easily screwed in the bottom of the snow-gripper by means of a wrench or a special key made for that purpose.

40 In Fig. 1, 1 are the two flanges which rest on the top of the sole edges and 3 the two or

more calks, which by fastening, press the sole tight to the flanges 1 as shown in Fig. 3.

In Fig. 2 one of the calks is shown in two views. 2 is the part of the calk into which 45 threads are cut to be screwed in the bottom of the body 4 of the snow-gripper (Fig. 1), and 5 is the edge in chisel form, by which the firm grip on the surface of the ground 50 is obtained. At 6 the calk is so formed as 55 to give a good hold for a wrench or special key.

I claim as my invention:

1. An anti-slipping means comprising a body adapted to underlie the sole of a shoe, 55 a flange at each end adapted to embrace the edge of the shoe sole, and calks mounted in said body and arranged to be brought into contact with the bottom of said shoe sole to clamp the device in place. 60

2. An anti-slipping means comprising, in combination, a relatively narrow body, a flange at each end thereof produced by turning the ends inward, and calks having 65 threaded connection with the body and adapted to be moved into engagement with the sole of a shoe on which the device is placed for clamping said device on the shoe sole.

3. An anti-slipping means comprising a 70 body adapted to underlie the sole of a shoe, inwardly turned flanges at the ends thereof for engagement with the edge of the sole, and calks provided with chisel shaped outer 75 ends and screw threaded inner ends, said inner ends adapted to pass through the body and being of sufficient length to project beyond the inner face thereof for engagement with the shoe sole to draw the flanges into firm engagement with the edge of said sole.

FRED GUSTAF BROMAN.
